UNITED STATES PATENT OFFICE.

LEWIS G. OLMSTED, OF PERU, ILLINOIS.

FLOOR, WALL, OR CEILING PLATE.

No. 835,635.

Specification of Letters Patent.

Patented Nov. 13, 1906.

Application filed January 23, 1906. Serial No. 297,481.

To all whom it may concern:

Be it known that I, LEWIS G. OLMSTED, a citizen of the United States, residing at Peru, in the county of LaSalle and State of Illinois, 5 have invented certain new and useful Improvements in Floor, Wall, or Ceiling Plates, of which the following is a specification.

The object of my invention is to provide an improved ceiling, wall, or floor plate for 10 hot-water pipes or the like, which will embody a construction whereby it will snugly fit the pipe without liability of displacement, which may be readily applied, which will be durable in construction and graceful in appearance, and which may be readily detached whenever desired.

With these and other objects in view, as will more fully appear as the description proceeds, the invention consists in certain constructions and arrangements of parts, herein-after fully described and claimed.

For a full description of the invention and the merits thereof and also to acquire a knowledge of the details of construction of 25 the means for effecting the result, reference is to be had to the following description and accompanying drawings, in which—

Figure 1 is a perspective view of my invention, illustrating it applied. Figs. 2 and 3 30 are side elevations, Fig. 2 illustrating the parts locked together, and Fig. 3 illustrating the position of the parts by which it is necessary to strain the two parts or sections transversely to completely lock them. Fig. 4 is a bottom plan view of the two parts separated. Fig. 5 is a transverse sectional view on the line $x-x$ of Fig. 4, looking in the direction of the darts. Figs. 6 and 7 are detail perspective views.

Corresponding and like parts are referred to in the following description and indicated in all the views of the drawings by the same reference characters.

My improved ceiling, wall, or floor plate 45 comprises two ring-like sections 1 and 2, each of which is substantially semicircular in shape, so that when placed together the two parts or sections will constitute a ring designed to embrace a hot-water pipe or the like. The two sections are substantially 50 ogee in shape in cross-section, the curved portions thereof terminating in a substantially perpendicular base-rim 3. Each of the two sections or parts is provided with a substantially perpendicular and semicircular flange 4 on its under side, near, but slightly

spaced, from its inner margin. The flanges are preferably integral with their respective sections, and each flange is provided with four slots 5, as shown. The slots 5 are located one near each end of a flange, and the other two are located comparatively close together near the middle of a flange. A spring 6 is secured in each of the flanges 4, and in the preferred construction each of the 65 springs 6, which in the present instance is a plate or leaf spring, but not necessarily so, has its ends passed through and secured in the end openings or slots 5 of the flanges, while its middle portion extends in two directions through two intermediate openings or slots 5, that are grouped substantially close together at the middle of the flange. To secure each of the springs 6 in place, its ends are passed through the intermediate or 70 middle slots 6 from the outside of the flange and on an incline, and the ends are thence diverged and extend through the end openings or slots 5 of the flange, so as to be retained in place. In the operation of insertion, as soon as the middle portion of the spring passes the intermediate or underneath bulge of the section of the ring it will fly or spring into place. By this construction the springs themselves 75 are permitted to have a maximum resiliency, while at the same time they securely hold themselves in place without any other fastening means and are sufficiently stiff to hold the sections tightly around the pipe or the like when the sections are locked together. 80 Furthermore, the exact construction of springs disclosed results in presenting four bow-spring portions 6^a, which project beyond the central opening in the ring constituted by the two sections 1 and 2 and which bear 85 at four equidistant points against the pipe, so as to equally distribute the pressure to an advantageous degree.

In order to lock the sections together, the section 2 is provided on its under side with 90 two circular sockets 7 and 8, formed in flattened surfaces 7^a and 8^a, projected from the under side of the section at the ends thereof. The section 1 is provided at one end with a lateral extension 9, which is 95 formed with an upwardly-projecting lug 10, whose upper face is preferably flattened, as shown, and which is designed to fit into the socket 7 of the section 2 and to constitute a pivot. The section 1 is provided at its other 100 end with a corresponding extension 11, on which is formed an upwardly-projecting stud

12, which is preferably round or semispherical, as shown. The stud 12 is designed to be seated in the correspondingly-shaped socket 8 of the section 2, so as to hold the 5 two sections together in combination with the lug and-socket 9 and 7. The section 2 is provided at its end adjacent the socket 7 with a radially-extending ledge 13, which projects out from its end, which conforms to the 10 general cross-sectional shape of the section, and which is recessed or located below the outer face thereof. The flange 4 of the section 2 is projected out at one side flush with the edge of said ledge, as shown. When it is 15 desired to lock the two sections 1 and 2 together around the pipe, the lug 10 is seated in its socket 7, and the two parts are then swung together on the lug as a pivot until the ledge 13 is seated underneath and is overlapped by the adjacent edge 14 of the section 1. As the two sections 1 and 2 are substantially alike, except as specifically herein described, it will be understood that when the edge 14 overlaps the ledge 13 the round stud 20 12 of the section 1 will abut against the adjacent end of the section 2. Hence, to permit the stud to seat itself in its socket 8 to lock the two sections together, it is necessary to slightly strain the two sections in a trans- 25 verse plane, so as to allow the said stud to snap into its socket. To facilitate this action, the flattened surface 8^a, in which the socket 8 is located, is provided at its outer end with a beveled surface 15, which leads 30 toward the socket 8.

35 From the foregoing description, in connection with the accompanying drawings, the operation of clamping the two sections 1 and 2 around the pipe is believed to be manifest to any one skilled in the art to which this invention pertains.

Preferably, to unlock the two sections 1 and 2 in order to remove them from the pipe, I have provided the section 2 at one end with 40 a preferably triangular-shaped recess 16, extending from its outer side or margin and at the base thereof toward the socket 8, and I have provided the lateral extension 11 of the socket 1 with a corresponding recess 17 on 45 its upper side. By means of this provision any pointed tool may be inserted in the opening formed by the two recesses 16 and 17, so as to spring those ends of the sections apart and carry the stud 12 out of engagement 50 with its socket 8, so that the two sections may be swung apart on the lug 10 and socket 7 as a pivot and be readily detached from 55 each other.

It will be seen that I have provided an improved construction of floor, wall, or ceiling plate for steam or hot-water pipes or the like which will be durable in construction and efficient in operation to securely maintain itself on the pipe independent of other fastening means, which will thereby, as well as by 60 its cross-sectional curvature and other constructive features, present a graceful appearance, and which will, owing to its overlapping edges and closely-fitting characteristics, be practically proof to dust and sound or odors 65 and which may be readily applied to a pipe and as readily detached therefrom.

Having thus described the invention, what is claimed as new is—

1. A device of the character described, 70 comprising two sections each of which is provided with a substantially perpendicular flange, each flange being formed near its ends with openings and with openings close together near its middle, springs having their 75 middle portions inserted through the middle openings of the flanges with their ends inserted in and retained by the end openings of the flanges, said springs being bowed from their middle portions to each end and arranged to engage a pipe or the like at four 80 equidistant points, and means for detachably securing said sections together.

2. A device of the character described, comprising two sections arranged to clamp 90 around a pipe, one of said sections being provided at each end with a socket, and at one end with a beveled surface leading toward said socket and a recess at its outer side also leading toward said socket and at its other 95 end with a radial ledge, and the other section being provided at each end with a lateral extension, one of said extensions being formed with an upwardly-projected lug designed to be seated in one socket of the first-named 100 section, a ledge thereof being overlapped by an adjacent end of said other section, and the other lateral extension being formed with an upwardly-projected stud designed to be seated in the other socket and with a recess opposite to the recess in the first-named section, 105 the said two recesses constituting an opening for the insertion of a tool or the like to spring the said sections apart.

In testimony whereof I affix my signature 110 in presence of two witnesses.

LEWIS G. OLMSTED. [L. S.]
